JAMES P. TIBBITS, OF NEW YORK, N. Y.

Letters Patent No. 97,993, dated December 14, 1869.

IMPROVED FOOT AND KNEELING-STOOL FOR CHURCHES.

The Schedule referred to in these Letters Patent and making part of the same

To all whom it may concern:

Be it known that I, JAMES P. TIBBITS, of the city, county, and State of New York, have invented certain new and useful Improvements in Foot and Kneeling-Stools for Churches; and I do hereby declare that the following is a full, clear, and exact description of the same, reference being had to the accompanying drawings, making a portion of this specification, and in which—

Figure 1 is a vertical transverse sectional view, showing my invention as arranged for use as a footstool.

Figure 2 is a like view, representing the same adapted for use as a kneeling-stool.

Similar letters of reference indicate corresponding parts in both figures.

This invention is designed to furnish a stool which, in churches, may be used either as a footstool or as a kneeling-stool, or substitute for a hassock, as may be desirable and appropriate at different portions of the church-service.

It consists in a box-shaped stool, having two cushioned sides, and hinged, or otherwise attached to the floor, in such manner, that when turned forward into one position, it may serve as a footstool, and when turned back in a reverse position, as a kneeling-stool.

The invention further consists in so combining the stool, as thus constructed, with the longitudinal pew-seat partition in front of it, that any noise which might otherwise occur, from the striking of the edge of the stool upon the floor, when the stool is turned forward, is wholly obviated.

To enable others to understand the nature and construction of my invention, I will proceed to describe it, with reference to the drawings.

The pew-seat, in connection with which the stool is to be used, is shown at A; and B indicates the stool. This latter is made of wood, or other suitable material, and is of the box-like shape illustrated in cross-section by the drawings, its two sides, *a* and *b*, being attached at their extremities to the end-pieces *c*. The outer surfaces of these two sides *a* *b* are, furthermore, cushioned, covered, or upholstered with any suitable soft, yielding, or elastic stuff or fabric, as represented at *a'*.

The stool is placed in front of the pew-seat A, in a position parallel therewith, and at a suitable distance therefrom. Its end-pieces *c*, at their corners *b'*, are hinged, pivoted, or otherwise attached to the floor, so that the stool may be turned bodily forward and back, upon the axis thus constituted.

The sides *a* *b* of the stool are situated in planes, at such an angle to each other as will enable each side to

serve its purpose in the most satisfactory manner, when the stool is brought into one position or the other, as the case may be.

Underneath the pew-seat, shown in dotted outline in the drawings, forward of the one to which the stool is adjunctive, is the usual longitudinal partition C, occupying, of course, a position parallel with that of the stool. This partition is, furthermore, at such distance from the axis or point at which the stool is attached to the floor, that when the stool is turned forward, for use as a footstool, as shown in fig. 1, the cushioned surface of its side *b* will come in contact with the flat surface of the partition, and, by arresting its movement, without slamming, and without contact with the floor, of the edge of the just-mentioned side, effectually prevents the noise which would otherwise occur, to the annoyance of the congregation, when the stool is thrown forward.

It will be seen from the above description, that when the stool is turned forward, as just previously herein explained, with the side *a* uppermost, the feet of the occupant of the pew-seat A may be placed upon, and supported by the said uppermost side, in the same manner as by an ordinary stool. And furthermore, that when the stool is turned back, as represented in fig. 2, with the side *b* uppermost, the same will be in such relation with the pew-seat, that the occupant of the latter may kneel upon the stool with the same facility as upon an ordinary stool, cushion, or hassock.

The device is thus made to serve a double purpose, adapting it for use, as may be desired, at different portions of the church-service.

In practice, it is preferred to extend the cushioning of the side *a* over the outer edge thereof, in order that no noise may result by its contact with the floor, when the stool is turned back, as previously herein set forth.

In addition to this, it is in some cases advisable to provide the aforesaid edge with two or more small knobs of India rubber, or equivalent elastic substance, attached to the edge by any suitable means.

What is here claimed, and desired to be secured by Letters Patent, is—

The stool B, constructed with sides *a* *b*, at right angles, or thereabout, to each other, and hinged, pivoted, or otherwise connected with the floor, in combination with the partition C, substantially as shown as described, for the purposes set forth.

JAS. P. TIBBITS.
